UNITED STATES PATENT OFFICE.

GEORGE S. HILL, OF BRADFORD, MASSACHUSETTS, ASSIGNOR, BY MESNE ASSIGNMENTS, TO THE SINGER MANUFACTURING COMPANY, A CORPORATION OF NEW JERSEY.

BUTTONHOLE-SEWING MACHINE.

No. 800,153.

Specification of Letters Patent.

Patented Sept. 26, 1905.

Divisional continuation of application Serial No. 677,151, filed April 11, 1898. This application filed June 26, 1901. Serial No. 66,076.

To all whom it may concern:

Be it known that I, GEORGE S. HILL, of Bradford, in the county of Essex and State of Massachusetts, have invented certain new and useful Improvements in Buttonhole-Sewing Machines, of which the following is a specification.

This invention relates to machines for sewing buttonholes, and has for its object to provide certain improvements in the same where-
10 by machines of this class are greatly simplified in construction and rendered more highly ef-
ficient in operation.

To these ends the invention consists of a buttonhole-sewing machine possessing certain
15 features of construction and relative arrangement of parts, all as hereinafter described in connection with the embodiment of the invention illustrated upon the drawings, the partic-
ular features of novelty being pointed out in
20 the claims hereunto annexed.

Reference is to be had to the accompanying drawings, and to the letters marked thereon, forming a part of this specification, the same letters designating the same parts or features,
25 as the case may be, wherever they occur.

Of the drawings, Figure 1 represents in full elevation a buttonhole-sewing machine embodying the invention, the bed and bed-plate being broken away to show the parts beneath
30 the said plate. Fig. 2 represents a rear elevation of the same, the bed and bed-plate being likewise broken away in this view. Fig. 3 represents a front elevation with the bed-plate raised into vertical position to show the parts
35 mounted therebeneath. Fig. 4 represents a machine partially in plan view and partially in section. In this view the bed-plate is broken away to the right of the turret, so as to show the mechanism for transmitting movement to
40 the clamp-carrier and to the mechanism for partially rotating or oscillating the upper and the under needle. Fig. 5 represents an end view of the machine, partially in section. Fig. 6 represents a section through the turret.
45 Fig. 7 represents a horizontal section through the hanging arm. Fig. 8 represents a trans-
verse section through the machine on the line
8 8 of Fig. 1. Fig. 9 represents in sectional view the power-transmitter and the devices
50 which intermittently rotate the same. Fig. 10 represents in plan view the clamps. Fig. 11 represents in section the clamps and the device for spreading them, being a section on the line 11 11 of Fig. 10. Figs. 12 and 13

represent the device for spreading the clamp. 55
Fig. 14 shows the hooked link which controls the automatic stop.

Referring to the drawings, in the embodiment of the invention therein shown and selected for the purpose of illustration the base 60 A, the bed-plate A' hinged thereto, and the overhanging arm A² may be of any preferred construction, my invention not relating to these parts, but to the mechanism which I shall subsequently describe as being supported 65 thereby.

Inasmuch as this application is a divisional continuation of application Serial No. 677,151, filed by me April 11, 1898, which has become Patent No. 684,241, reference may be had to 70 said patent for a description of such parts as are illustrated in the accompanying drawings, but not herein described.

Mounted in suitable bearings in the over-
hanging arm A² is the main shaft a, from which 75 power is imparted to the upper and the under needles and mechanism for partially rotating or oscillating the same. The said main shaft a is provided with a crank a¹⁷, from which a connecting-rod d extends to a crank-arm d' 80 upon the end of the lower shaft d². As the shaft a rotates it imparts an oscillatory or rocking movement to the shaft d², as will be readily understood. From this shaft power is transmitted to the various parts of the ma- 85 chine, including those which accomplish the movement of the clamp-carriage.

The cam-wheel g' is secured upon a stud-
shaft g², depending from the bed-plate A', and secured upon its hub g³ is a disk g⁴. (Shown 90 in dotted lines in Figs. 4 and 9.) This disk g⁴ is provided with a series of notches or sockets g⁵, in which are placed loose rolls g⁶, bearing against springs g⁷, placed in the said sockets. A ring g⁸ surrounds the periphery of the 95 disk g⁴ and rests on a flange thereon, being provided with a top plate g⁹, as shown in Fig. 1, to hold the rolls g⁶ in place. The ring g⁸, the disk g⁴, and the rolls g⁶ constitute friction-clutch mechanism for imparting a step-
by-step movement to the cam, this being accom- 100 plished by oscillating the member g⁸. The said member or ring g⁸ has an outwardly-projecting arm g¹⁰, connected by a ball-and-socket joint with a link g¹¹, having its rear end connected to an arm g¹², extending upwardly from the shaft d². 105

When the machine is set in motion, power

is imparted from the main driving-shaft to the shaft d^2 , and as the latter is oscillated or rocked the cam-wheel g' is rotated with a step-by-step movement. From this cam-wheel g' power is transmitted to various parts of the machine to accomplish various functions. One of the offices performed by the cam is the movement of the clamping device, which I shall now proceed to describe.

10 The clamp-carrier consists of a block h , as shown in Fig. 4, to which are secured brackets h' , which are pivoted upon the said block and to which the upper and lower members of each clamp are secured. A stud h^3 passes through each bracket and forms the pivot around which it may swing. The members of each clamp comprise an under clamping-bar h^3 , secured to the bracket h' , and upper clamping-bar h^4 , secured upon a boss or lug h^5 , arising from the said bracket. On its end each upper clamping-bar h^4 is provided with a pivotal presser-foot h^6 , having an inwardly-curved heel h^7 , the heels of the two presser-feet being almost contiguous, as shown in Fig.

15 20 25 30 35 40 45 50 55 60 65 70 75 80 85 90 95 100 105 110 115 120 125 130

10. The upper clamping-bars h^4 are made of spring metal, whereby by their own resiliency they clamp the work against the lower clamping-bars. One of the upper clamping-bars h^4 is provided with a cross-bar h^8 , which projects under the other bar h^4 of the upper clamp and causes it to rise therewith when it is lifted. To raise the upper bars of the clamps, a pin is passed vertically through the turret, being supported in a sleeve h^{10} , having its lower end secured in the plate e^2 before referred to, these parts being shown in Fig. 6. When the turret is in the proper position, the said vertical pin is below the cross-bar h^8 and also registers with a pin h^{11} , mounted upon the end of an arm h^{12} , secured to a sleeve h^{13} , loosely mounted on the shaft d^2 . (See Figs. 1 and 6.) The pin h^{11} is on a block h^{14} , pivoted in an ear in the arm h^{12} , and a spring h^{15} in a socket in the said arm bears against the block h^{14} , so as to hold the pin h^{11} in its proper position, although the latter is free to swing relatively to the arm, when the arm is raised and the pin h^{11} enters the aperture in the sleeve h^{10} as it forces the vertical pin in the turret upwardly. The sleeve h^{13} is provided with a rearwardly-extending arm h^{16} , connected by a link h^{17} with a treadle, (not shown,) so that upon depressing the treadle the sleeve is rocked and the pin h^{11} is lifted to raise the upper bars of the clamp and permit the work to be moved. The sleeve may be rocked, however, by any other mechanism that may be desired.

To effect the movement of the clamp-carrier, I employ the following devices: The arm i is pivoted to a stud i' , projecting downwardly from the bed-plate at the left end thereof, in the rear of the shaft d^2 . It is formed near its free end into a cylindrical bearing-bracket i^2 to receive a pintle i^3 , hav-

ing a frusto-conical or flaring upper end i^4 , from which the threaded portion projects into an aperture in the clamp carrier or block h . The lower end of the pintle is reduced and threaded to receive a conical bearing-sleeve i^5 and a lock-nut i^6 . The ends of the bracket i^2 are flared to receive the said cones, whereby I provide for the taking up of wear of any of the parts through the adjustment of the cones. The arm i is projected a short distance beyond the bearing-bracket i^2 and is slotted, as at i^7 , to receive a stud i^8 , passed through the slotted end of a bell-crank lever i^9 , fulcrumed upon a stud i^{10} , depending from the bed-plate A' . By reason of the levers being connected by the stud passed through the socket the throw of the lever i , and consequently of the clamp-carrier, may be varied to suit the length of the buttonhole-slit. The arm i and the arm i^9 of the bell-crank lever are substantially in alinement with each other, as seen in plan. The other arm i^{12} on the bell-crank i^9 is provided with a trundle i^{13} , lying in a cam-slot in the cam-wheel g' , whereby as the cam rotates the bell-crank lever is oscillated to swing the arm i about its axis and effect the forward - and - backward movement of the clamp-carrier. This clamp-carrier being secured to the pintle i^3 is thus pivotally supported upon the end of the arm and is free to swing about the axis of the same. Therefore in order to effect sidewise movement of the front ends of the clamps the block h is provided with an arm i^{14} , having on its end a trundle projecting into a cam-slot g^{15} in the cam-wheel g' . The parts are so timed that the forward ends of the clamps are moved in a path almost similar in shape to the edges of the buttonhole-slit. The spreading of the clamps is effected by means of the devices illustrated more particularly in Figs. 11, 12, and 13.

Secured to the carrier or block h is a post j , which is hollow, as shown, and surrounding the post is a sleeve j' , which is conical near its lower end, as at j^2 . The upper end of the sleeve is threaded to receive an internally-threaded cap j^3 , held upward by a spring j^4 inside the hollow post, having its upper end abutting against a stud j^5 , pressed against a pin j^6 , inserted crosswise through the cap. The post j is provided at its upper end with ears or lugs j^7 , between which is pivoted a cam-lever j^8 , having its end extending through a slot in the cap and resting upon the pin j^6 .

When the end of the cam-lever is raised, as shown in Fig. 11, the spring j^4 forces the cap upward and raises the spreading-sleeve j' ; but when the end of the lever j^8 is depressed the cap is forced down and the conical portion j^2 of the sleeve wedges between the lower clamping-bars h^3 and swings each pair of clamping-bars about its rear-end pivot to spread their outer ends. The spreading-sleeve may

be adjusted to vary the spread of the clamp-bars, after which it is locked by a nut j^9 .

To accomplish the spreading of the clamp-bars automatically, the lever j^8 is provided with a pin j^{10} , projecting into a slot j^{11} in the end of a bell-crank lever $j^{12} n$, secured to an arm j^{13} , pivoted at j^{14} to the side of the overhanging arm a^2 , the arm n projecting into a slot in the bar a^4 . Connected to the end of the arm j^{13} by a ball-and-socket joint is a link k , which projects downward through the bed-plate a' and is provided on its end with a barb or hook k' . This hooked link k projects through a slot in the end of a two-armed lever $l l'$, pivoted between its ends upon a shaft m , arranged parallel to the cutter-shaft d^2 in the rear thereof. The lever is provided with a hub fast upon the shaft m , so that when it is rocked or tilted the shaft is rocked to accomplish a function to be subsequently set forth.

Arranged longitudinally in the arm l is a socket to receive a spring-pressed stud l^2 , which tends to throw the link k forward, so that its barb or hook will engage the end of the lever l . Pivoted to the opposite end l' of the lever is a rod l^3 , which hangs loosely into a socket in the end of a reciprocating bar l^4 , driven by the usual transmitter-shaft, (not shown,) from which movement is transmitted to the main driving-shaft of the machine through the belt before described. This transmitter-shaft is indicated at l^5 and it reciprocates the tubular bar l^4 through the medium of a crank l^6 , eccentric, or any other device that may be desirable. Normally the bar l^4 reciprocates without effecting any movement of the bar l^3 and the lever $l l'$, the rear end of the latter being normally raised by a strong spring l^7 , as shown in Figs. 5, 6, and 14. In order to temporarily connect the reciprocating part l^4 and the bar l^3 , a latch l^8 is pivoted to the pintle l^8 , (which connects the bar l^3 with the end of the lever l), and the hooked end of the latch is adapted to enter a notch l^9 in the tubular bar l^4 when the latter is in its highest position, as shown in Fig. 8. Normally the latch l^8 is held out of the notch by a dog l^{10} , (see Figs. 6 and 14,) pivoted in an ear on the bar l^3 . A dog l^{11} (see Figs. 6, 8, and 14) is pivoted upon the lever h^{16} and is held against a stud l^{12} , (see Figs. 6 and 14,) projecting out from the side thereof by a spring l^{13} , also resting against the shaft m . When the main treadle is depressed to draw the lever h^{16} downward, the pawl l^{11} slides by the end of the dog l^{10} ; but when the lever h^{16} is raised by the spring upon removing the foot from the treadle the dog or pawl l^{11} engages the end of the dog l^{10} and tilts it, throwing it out of the way of the latch l^8 , which upon the next reciprocation of the bar l^4 immediately enters the notch l^9 and a single reciprocation is imparted to the lever l by the bar l^4 . As the bar l^3 rises after having been once depressed, the end of the dog l^{10} strikes against the end

of the pawl l^{11} and is thrown back into its normal position to disengage the latch l^8 from the notch l^9 , the dog l^{11} being held from vertical movement by reason of its pressing against the shaft m , as shown in Fig. 8. When the front end of the lever $l l'$ was raised, the lower end of the link k entered the aperture therein, so that when the front end of the said lever $l l'$ is again depressed it draws down with it the hooked link k and swings the lever j^{12} to depress the arm j^8 and spread the clamp, it continuing to hold the link depressed until a tripping device consisting of a bell-crank lever s , pivoted on the stud i^9 , is actuated by a projection s' on the cam g' to disengage the link from the catch or lever l .

The downward movement of the lever j^{12} causes the starting of the machine, for secured to said lever is the arm n , the upper end of which projects into a slot in the bar a^4 , whereby when the arm j^8 is drawn downward to spread the clamps the automatic stop is thrown out of engagement with the cam a^{13} and the belt is shifted from the loose pulley a' to the fast pulley a^2 .

While the clamp-bars are raised the operator moves the work along underneath the clamp to place it in position for the next buttonhole, and as he removes his foot from the treadle and permits the bar h^{16} to swing upwardly the dog l^8 engages the dog l^{12} and throwing it out of its normal position permits the latch l^8 to drop into the notch l^9 in the reciprocating bar l^4 the next time it rises. Immediately upon the engagement of the latch with the bar l^4 the lever l is rocked, so that its free end engages the hooked link k' . The movement of the lever l also draws the link k downward and swings the bell-crank $j^{12} n$ about its stud j^{10} . This causes two things to happen: First, the arm j^8 is forced downward to cause the spreading of the work-clamps, which immediately closed upon the work when the foot was raised from the treadle and the bar h^9 in the turret returned to its normal position; and, second, it throws the automatic stop out of engagement with the fast pulley and shifts the belt a^3 thereto from the loose pulley. As the sewing progresses the clamp-carrier moves backwardly and slightly laterally until the stitching is complete almost the length of one edge of the buttonhole-slit. Then the wiper g upon the cam g' engages the roll f^8 upon the lever f^7 , and the bar f' is rocked to swing the segments $f^2 f^3$ and cause a partial rotation of the turret and the upper needle, whereby the needles sew around the enlarged end of the buttonhole-slit, making one-half of a revolution. Then the movement of the clamp-carrier is reversed and the sewing is completed upon the opposite edge of the buttonhole-slit. When the last stitch is almost completed, the cam projection s' on the cam-wheel engages a bell-crank lever s , pivoted upon the stud i^9 , and swings it suffi-

ciently to cause it to engage the hooked end k' of the link k and disengage it from the lever l . The link immediately rises, and the automatic stop is forced by the spring a^{15} into position

5 to stop the rotation of the needle-shaft, at the same time the lever j^5 is raised and the clamps are permitted to approach each other.

This application is a divisional continuation 10 of application Serial No. 677,151, filed by me April 11, 1898, which has become Patent No. 684,241.

Having thus explained the nature of the invention and described a way of constructing and using the same, although without attempting 15 to set forth all of the forms in which it may be made or all of the modes of its use, I declare that what I claim is—

1. A machine of the character described, comprising stitch-forming mechanism, a work-holder and means for producing a relative movement between said stitch-forming mechanism and work-holder to sew around a buttonhole, said work-holder comprising a work-clamp having upper and lower members, a 25 carrier on which said members of said clamp are pivotally supported, said carrier being pivotally supported to swing in any direction in a plane parallel to the plane of the work, means for operating said carrier, and means 30 for raising the upper members of the clamp.

2. A machine of the character described, comprising stitch-forming mechanism, a work-holder and means for producing a relative movement between said stitch-forming mechanism and work-holder to sew around a buttonhole, said work-holder comprising a work-clamp having members to lie respectively above and below the work, a carrier for 35 both members of said clamp, a swinging support to which said carrier is pivoted, and means for automatically actuating said support and said carrier.

3. A machine of the character described, comprising stitch-forming mechanism, a work-holder, and means for producing a relative movement between said stitch-forming mechanism and work-holder to sew around a buttonhole, said work-holder comprising a work-clamp having coacting members to lie 45 respectively one above and the other below the work, means enabling each of said members to be laterally spread, a carrier on which both clamping members are movably supported, and independent cam-actuating levers 50 for actuating said carrier to swing said members in a plane parallel to the plane of the work.

4. A machine of the character described, comprising stitch-forming mechanism, a work-holder, and means for producing a relative movement between said stitch-forming mechanism and work-holder to sew around a buttonhole, said work-holder comprising a work-clamp having coacting members to lie 60 respectively above and below the work, a piv-

oted carrier for the clamp, and cam-actuated levers for actuating said carrier to swing said members in a plane parallel to the plane of the work.

5. A machine of the character described, 70 comprising stitch-forming mechanism, a work-holder and means for producing a relative movement between said stitch-forming mechanism and work-holder to sew around a buttonhole, said work-holder comprising a work-clamp having coacting members to lie respectively above and below the work, a carrier for both members of said clamp, a swinging support to which said carrier is pivoted, and two separate levers for imparting to said 75 clamp a universal movement in a plane parallel to the work.

6. A machine of the character described, comprising stitch-forming mechanism, a work-holder and means for producing a relative movement between said stitch-forming mechanism and work-holder to sew around a buttonhole, said work-holder comprising a work-clamp having coacting members to lie respectively above and below the work, a piv- 80 otally-mounted support, automatic devices for swinging said support about its pivot, a work-clamp carrier pivotally mounted in said support and movable in a plane parallel to the 85 plane of movement of the support, and mech- 90 anism for actuating said carrier.

7. A machine of the character described, comprising stitch-forming mechanism, a work-holder and means for producing a relative movement between said stitch-forming mechanism and work-holder to sew around a buttonhole, said work-holder comprising a work-clamp having coacting members to lie 95 respectively above and below the work, a piv- 100 otally-mounted support, a clamp-carrier piv- 105 otally mounted on the support, and cam mechanisms for actuating the carrier and support independently of each other.

8. A machine of the character described, comprising stitch-forming mechanism, a 110 work-holder and means for producing a relative movement between said stitch-forming mechanism and work-holder to sew around a buttonhole, said work-holder comprising two 115 pivotally-mounted work-clamps having coacting members to lie respectively above and below the work, a pivotally-mounted support for said clamps, a pivoted lever for swinging said support about its axis of movement, and means for swinging said work-clamps on said 120 support.

9. A buttonhole-sewing machine comprising 125 stitch-forming mechanism, a work-holder and means for producing a relative movement between said stitch-forming mechanism and work-holder to sew around a buttonhole, said work-holder comprising a work-clamp having coacting members to lie one above and the other below the work, each member having 130 separable bars, a pivotally-mounted support

for said clamp to which said bars are movably attached, means for spreading the bars, and a pivoted lever for swinging said support about its axis of movement.

5 10. A buttonhole-sewing machine comprising a stitch-forming mechanism, a work-holder and means for producing a relative movement between said stitch-forming mechanism and work-holder to sew around a buttonhole, said work-holder comprising a work-clamp, a carrier therefor, an oscillatory arm on which said carrier is pivotally mounted, a lever for operating said arm to move said carrier and clamp in one direction and an independent lever for operating said carrier to move said clamp laterally at an angle to the direction of the first movement.

11. A buttonhole-sewing machine comprising stitch-forming mechanism, a work-holder and means for producing a relative movement between said stitch-forming mechanism and work-holder to sew around a buttonhole, said work-holder comprising a work-clamp having members to lie one above and the other below the work, a carrier for said clamp, a swinging support on which said carrier is pivoted and carried, means for swinging the carrier on its support and means including a cam and lever for automatically swinging said support about its pivot.

12. A buttonhole-sewing machine comprising stitch-forming mechanism, a work-holder and means for producing a relative movement between said stitch-forming mechanism and work-holder to sew around a buttonhole, said work-holder comprising a work-clamp having members to lie one above and the other below the work, a pivotally-mounted support, automatic devices including a cam and a lever for swinging said support about its pivot, a work-clamp carrier pivotally mounted in and car-

ried by said support and movable in a plane parallel to the plane of movement of the support, and mechanism for actuating said carrier, comprising an arm on said carrier and a cam for operating said arm.

13. A buttonhole-sewing machine comprising stitch-forming mechanism, a work-holder and means for producing a relative movement between said stitch-forming mechanism and work-holder to sew around a buttonhole, said work-holder comprising a work-clamp having coacting members to lie one above and the other below the work, a pivoted carrier on which the clamp members are movably supported, and independent cam-actuated levers for actuating said carrier to swing said members universally in a plane parallel to the plane of the work.

14. A buttonhole-sewing machine comprising a work-clamp having members to clamp and hold the work between them, and a stitch-forming mechanism, of which instrumentalities one is movable with respect to the other to sew around a buttonhole, a pivoted carrier for the movable instrumentality, means for swinging said carrier, a pivoted support for said carrier, and mechanism for swinging the support.

15. A buttonhole-sewing machine comprising two pivotally-mounted work-clamps, a post between said clamps, a conical sleeve movable on said post, a spring bearing against said sleeve, and a cam-lever fulcrumed on said post and arranged to force said sleeve against said spring to separate said clamps.

In testimony whereof I have affixed my signature in presence of two witnesses.
